[57] CLAIM

The ornamental design for a specimen cup holder, as shown and described.

DESCRIPTION

FIG. 1 is a perspective view of a specimen cup holder showing our new design, with a specimen cup in broken lines for illustrative purposes only and forming no part of the claimed design;

FIG. 2 is a rear elevational view thereof;

FIG. 3 is a front elevational view thereof;

FIG. 4 is a side elevational view thereof;

FIG. 5 is a side elevational view thereof, opposite that shown in FIG. 4;

FIG. 6 is a top plan view thereof;

FIG. 7 is a bottom plan view thereof;

FIG. 8 is a perspective view thereof, with the handle in folded position; and,

FIG. 9 is a perspective view thereof, with the handle in a second folded position.
